DESIGN FOR A REFRIGERATED DISPLAY
CASE

Russell E. Davis, St. Louis, Mo., assignor to Hussmann-Ligonier Company, St. Louis, Mo., a corporation of Delaware

Application February 7, 1946, Serial No. 126,358

Term of patent 14 years

(Cl. D80—11)

To all whom it may concern:

Be it known that I, Russell E. Davis, a citizen of the United States and a resident of the city of St. Louis and State of Missouri, have invented a new, original, and ornamental Design for a Refrigerated Display Case, of which the following is a specification reference being had to the accompanying drawing, forming part thereof.

Fig. 1 is a front perspective view of a refrigerated display case, showing my new design,

Fig. 2 is an end elevational view looking at the opposite end from that shown in Fig. 1; and

Fig. 3 is a vertical cross-sectional view taken on line 3—3 of Fig. 1.

I claim:

The ornamental design for a refrigerated display case, as shown.

RUSSELL E. DAVIS.
